US00D942966S

(12) **United States Design Patent** (10) **Patent No.:** **US D942,966 S**
Wang et al. (45) **Date of Patent:** **** Feb. 8, 2022**

(54) **SPEAKER**

(71) Applicant: **Logitech Europe S.A.**, Lausanne (CH)

(72) Inventors: **Wenwei Wang**, Hsinchu (TW);
Ming-Hsiang Weng, Hsinchu (TW);
Jeremy David Baker, Homestead, FL
(US); **Olivier Gregoire**, Oakland, CA
(US)

(73) Assignee: **Logitech Europe S.A.**, Lausanne (CH)

(**) Term: **15 Years**

(21) Appl. No.: **29/779,461**

(22) Filed: **Apr. 19, 2021**

Related U.S. Application Data

(63) Continuation of application No. 29/712,319, filed on Nov. 7, 2019, now Pat. No. Des. 919,599, which is a continuation of application No. 29/602,251, filed on Apr. 28, 2017, now Pat. No. Des. 871,372.

(57) **CLAIM**

The ornamental design for speaker, as shown and described.

DESCRIPTION

FIG. 1 is a perspective view of a speaker showing a first embodiment of our new design;

FIG. 2 is a second perspective view thereof;

FIG. 3 is a front elevational view thereof;

FIG. 4 is a right side elevational view thereof; and

FIG. 5 is a left side elevational view thereof.

FIG. 6 is a perspective view of a speaker showing a second embodiment of our new design;

FIG. 7 is a second perspective view thereof;

FIG. 8 is a front elevational view thereof;

FIG. 9 is a right side elevational view thereof; and,

FIG. 10 is a left side elevational view thereof.

The broken lines depict portions of the speaker in which the design is embodied that form no part of the claimed design.

1 Claim, 6 Drawing Sheets
